UNITED STATES PATENT OFFICE.

MURRELL R. DE FRANCE, OF BELLEVUE, PENNSYLVANIA.

SHELL FOR COMPOSITION BRAKE SHOES.

Application filed July 23, 1925. Serial No. 45,551.

To all whom it may concern:

Be it known that I, MURRELL R. DE FRANCE, a citizen of the United States, residing at Bellevue, in the county of Allegheny and State of Pennsylvania, have invented a new and useful Improvement in a Shell for Composition Brake Shoes, of which the following is a specification.

This invention relates to a pressed steel 10 brake shoe shell for use as a container for frictional composition to provide a complete brake shoe.

There are a number of features, some of which are in partial conflict, which are 15 highly desirable in providing a satisfactory pressed steel shell for use with a composition filler of frictional material. These features are as follows: A shell for a composition filler which is pressed from a blank 20 which may be easily formed, a blank which may be pressed to form the containing shell without tearing the metal at any point, a shell which is strong at the areas subjected to greatest stress, a shell which protects and 25 holds together the composition filler at the points where protection and binding are most needed, a shell which presents a relatively small area of metal to the wheel to which the brake shoe is applied during 30 wearing away of the shoe and throughout the entire useful life thereof.

The desirability of one or more of such features is fully explained in various prior 35 patents, among which are the patent to De France No. 1,114,343, dated October 20, 1914, the patent to De France No. 1,303,173, dated May 6, 1919, the patent to Pettis No. 1,503,514, dated August 5, 1924, and the application to De France Serial No. 743,937, 40 filed Oct. 16, 1924.

In the accompanying drawings Figure 1 is a plan view of a blank in condition to be pressed into the brake shoe shell of the present invention; Figure 2 is a cross section view thereof on the line 2—2 Figure 1, showing in dotted lines the position assumed by the metal along the edges of the blank in forming the sides of the shell; Figure 3 is a side elevation of the completed brake shoe 45 with the composition filler of frictional material in the shell, Figure 4 is a bottom plan view of the shell without the composition filler therein; Figure 5 is a cross sectional view on the line 5—5 Figure 3; Figure 6 is 50 an end elevation of the brake shoe; Figure 55 7 is a fragmentary elevation of a portion

of one side of the brake shoe shell, showing the shell in unused or very slightly used condition; Figure 8 is a bottom plan view of the shell portion shown in Figure 7, 60 showing the distribution of the metal which comes into contact with the tread of a wheel; Figure 9 is a fragmentary elevation of a portion of one side of the brake shoe shell, showing the shell partially worn down; and 65 Figure 10 is a bottom plan view of the shell portion shown in Figure 9, illustrating the distribution of the metal which comes into contact with the tread of a wheel.

In the drawings the reference numeral 1 designates generally the blank from which the brake shoe shell of the present invention is pressed. This blank is rolled to provide a central longitudinally extending portion of relatively great thickness, and side 70 portions 3 tapering outwardly to the edges of the blank. The central portion 2 of the blank becomes eventually the back and ends of the shell; and the side portions 3 of the blank become the sides of the shell, while 75 providing some metal which goes into the ends.

The blank is then punched into the form shown in Figure 1. By this punching operation the central portion 2 of the blank is 80 provided with slots 4 for the attachment of a lug to engage the brake shoe hanger, and with slots 5 for the attachment of the end lugs of the brake shoe. The side portions 3 of the blank are also punched so that 85 they form a plurality of strips or tabs 6, with intervening apertures 7 which extend completely to the edge of the blank.

The apertures 7, punched from the side portions of the blank, are of greatest width 90 adjacent the central portion of the blank and decrease in width gradually toward the edge of the blank. Correspondingly the strips 6 are of least width adjacent the central portion of the blank, and increase in 95 width gradually toward the edge of the blank.

In the pressing operation, the sides and ends are folded down so that the central portion 2 of the blank becomes the back 9 100 and ends 10 of the brake shoe shell, while the side portions 3 of the blank become the sides 11 of the brake shoe shell. During this pressing operation a certain amount of metal from the side portions of the blank 105 flows into the end portions 10 of the shell. In order to accommodate this surplus metal,

the dies are so formed as to produce a shell with vertically extending ribs or corrugations 12 on the end portions 10 of the shell. As the pressed shell assumes an arcuate form 5 to correspond to the curvature of a wheel, the lower extremities 13 of the side strips 6 are drawn closer together in the completed shell than their position in the unpressed blank. This may be observed by a 10 comparison of Figures 1 and 3 of the drawings.

In brake shoe shells having perforated or reticulated sides, as heretofore designed, a relatively great loss has been suffered due to 15 pulling or tearing the sides of the shell from the back during the pressing operation. With this form, however, the relatively great amount of metal along the line of the fold, and at the base of the side strips 6, 20 prevents such tearing and pulling away.

The back 9 of the brake shoe shell, being formed of the thick central portion 2 of the blank, is of relatively great thickness and strength. It is thus enabled to resist the 25 forces tending to pull the shoe apart in use after the body has become worn thin.

When the brake shoe shell, designated generally by the reference numeral 14, has been pressed to form; the filling block 15 of a suitable frictional composition, in plastic condition, is pressed thereinto. As the side apertures 7 occupy each a relatively great area, no more pressure is necessary to force the composition through them than 30 need be exerted in pressing the filling composition into a shell having sides of a continuous extent of material. All varieties of composition which may be used are so composed that after being pressed into the 35 brake shoe shell they harden upon baking or mere exposure to the air.

As the width of the apertures is least adjacent the lower edges of the sides, the filling composition hardening in the apertures 45 causes them to form an anchorage for the entire block of filling composition equal to that secured by the provision of reticulated or perforated sides. Since the greatest area embraced by the apertures is adjacent the 50 back of the shell, their form also contributes to the rapid and perfect drying and hardening of the composition. This is the case because an increased area of the sides of the 55 filler is exposed to the action of the air in the portion of the filler which has one entire face covered by the back of the shell.

In actual use of the brake shoe, the only 60 portions of the sides 11 which are subjected to stress are the areas adjacent the ends and close to the back of the brake shoe. At such areas there is a turning moment, due to the 65 engagement of the brake shoe with the wheel to which it is applied, which tends in some degree to pull the brake shoe apart. As a special precaution in meeting this tendency,

the apertures 16, which are adjacent the ends of the shell are made of lesser extent than the other apertures 7 in the sides. This provides a greater extent of metal at these general areas 17 on the sides of the shell. 70

During handling of the brake shoe prior to its mounting for use, and even after such mounting, the composition filler of the brake shoe is susceptible to chipping or cracking due to blows received by the lower edges 75 of the filling block. In this connection it should be noted that the widest portions of the side strips 6 of the shell lie along these edges and serve to adequately protect the same during handling and while the depth 80 of the brake shoe remains sufficient to render probable the reception of blows along the edges of the shoe.

It is a well known fact that injury to the 85 tread of a wheel to which a brake shoe is applied results from the presentation of a relatively great area of the hard metal of the brake shoe shell to the tread of the wheel. It is therefore desirable to avoid the presentation of an excessive area of such metal, while retaining the other characteristics which are desirable in a brake shoe shell.

It has been previously noted that the 90 portions 3 of the blank from which the shell is pressed are tapered outwardly toward the side edges of the blank. This naturally results in the production of a shell which has sides tapering downwardly toward their lower edges. The thickness of the metal of the side strips 6 is thus greatest where their 95 width is least, and is least where their width is greatest. 100

By proportioning the width of the strips 6 at any point along their vertical extent with the thickness of the strips at such point, the area of metal in contact with the tread of a wheel may be maintained constant at all times during the useful life of the brake shoe. In computing such proportion, regard 105 should of course be given to the effect produced by imposing the necessary arcuate form on the shell during the pressing operation.

Figures 7, 8, 9 and 10 illustrate the 110 constant area of metal presented to the tread of a wheel during the wearing down of a brake shoe shell. By comparing the effective areas 18 of the strips as shown in Figure 8 with the effective areas 19 of the strips as shown in Figure 10, it is found that the 115 sum of the areas 18, and the sum of the areas 19 is approximately equal. This is true at any stage of wear during the effective life of the brake shoe. 120

It will be readily understood that the 125 brake shoe shell illustrated and described herein presents an unusual combination of the qualities found most desirable in an article of such nature. 130

What I claim is:

1. A brake shoe shell for use with a filling of frictional composition formed with integral back end and side walls, the side walls of the shell comprising a plurality of strips with intervening apertures, said strips being so proportioned that the total areas of metal presented by the strips of one side is approximately equal at any point along the vertical extent of the shell as the brake shoe wears away in use.

2. A brake shoe shell for use with a filling of frictional composition formed with integral back end and side walls, the back wall being of relatively great thickness, and the side walls comprising a plurality of strips tapering in thickness from the back downwardly to the edges of the sides and having their width tapering upwardly to

the back of the shell with intervening apertures between strips.

3. A brake shoe shell for use with a filling of frictional composition formed with integral back end and side walls, the back wall being of relatively great thickness, and the side walls comprising a plurality of strips tapering in thickness from the back downwardly to the edges of the sides and having their width tapering upwardly to the back of the shell with intervening apertures between strips, said strips being so proportioned that the total area of metal presented by one side is approximately equal at any point along the vertical extent of the shell as the brake shoe wears away in use.

In witness whereof, I hereunto set my hand.

MURRELL R. DE FRANCE.
